UNITED STATES PATENT OFFICE

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY

RIVET CUTTING GUN

Application filed June 19, 1928. Serial No. 286,621.

This invention relates to fluid pressure tools and more specifically to large pneumatic hammers used in demolition work, as in cutting off bolt and rivet heads and punching out rivets, such tools being commonly referred to as rivet cutting guns. On account of their size and weight such tools frequently require at least two men to operate, one to direct the demolishing end of the gun and the other to control the motive fluid. A tool of this type strikes a single blow in one position of the throttle handle which is then moved to a different position to effect the return or non-working stroke of the piston.

One object of the invention is to provide an improved form of control valve for the motive fluid. Another object is to secure a full and forceful blow by providing for the time element involved in the manual throw of the valve to the forward position thereby to insure a full head of motive fluid upon the piston at the beginning of its forward stroke. Another object is to insure proper lubrication of the control valve and a lasting seal against the escape of motive fluid. Other objects will be apparent from the detailed description which follows.

In order to illustrate the invention one concrete embodiment thereof is shown in the accompanying drawings in which:

Fig. 1 is a side elevational view partly cut away and partly in section;

Fig. 2 is a sectional view substantially on the line 2—2 of Fig. 1;

Fig. 3 is a fragmentary sectional view substantially on the line 3—3 of Fig. 2; and

Figs. 4 and 5 are fragmentary sectional views similar to Fig. 3 showing the valve in different operative positions.

The embodiment of the invention chosen for the purpose of illustration comprises a fluid pressure hammer adapted for demolition work and comprising a long cylinder 6 providing a piston chamber within which reciprocates a free piston 7 which delivers its blow directly upon the shank of a working tool such as a rivet cutting chisel 8 which is supported in a guide bushing 9 threaded into a front head 10 secured to cylinder 6 and having a handle 11 for supporting the forward

end of the tool and directing it to the work. A heavy coil spring 12 may be interposed between guide bushing 9 and the forward end of cylinder 6 to absorb the blow of piston 7 and prevent breakage of the front head in the event that the working tool 8 is not in proper position. The cylinder may provide a free atmospheric vent or exhaust port 6a controlled by piston 7.

The rearward end of cylinder 6 has secured thereto in any suitable or desired manner a back head 13 having therein a cylindrical slightly tapered opening 13a rearwardly of the cylinder and disposed transversely to the axis of the latter. A closure 14 having a reduced bore 14a therethrough is provided at one end of bore 13a and is arranged to be secured to back head 13 in any suitable manner as by screw bolts 15. The rearward end of the back head 13 terminates in a boss 13b having a central threaded opening 13c for a fluid pressure conduit. Boss 13b also has a bore therethrough in which is rigidly secured a handle 16 for supporting the tool.

A cylindrical valve 17, of a size and taper to fit the bore 13a in the back head, is disposed therein to control the pressure fluid for operating piston 7. Valve 17 has a reduced portion 17a arranged to extend beyond the back head at one side and to have keyed thereto a handle 18 by which valve 17 is manually rotated or oscillated. Stops 19 and 20 (Fig. 1), are provided on the back head in position to be engaged by handle 18 and to limit its movement. Securing means, such as a nut 21, may be provided to hold handle 18 in place. The large end of valve 17 has a reduced axial extension 17b which projects through the bore 14a of closure 14 and therebeyond, the extension being threaded to receive a castle nut 22. Surrounding extension 17b and interposed between valve 17 and closure 14 are resilient means which may take the form of a coil spring 23 which yieldingly urges valve 17 into close contact with the tapered bore of valve chamber 13a. Nut 22 is set up just sufficiently to prevent valve 17 from sticking or tightly wedging in the bore 13a. The pressure fluid ports and passages and the means on valve 17 for controlling the

same are disposed substantially centrally of the valve.

In order properly to lubricate valve 17 and to prevent leakage of the pressure fluid from the central portion of the valve chamber, suitable means are provided adjacent the ends of the valve. Such means preferably take the form of annular grooves or recesses 17c in valve 17 adjacent the ends thereof, the grooves being filled with a suitable lubricant such as a relatively hard grease before the valve is inserted in its chamber.

The manner of controlling the operation of the tool and the various positions of the valve are shown in Figs. 3, 4, and 5 which also indicate, in dotted outline, corresponding positions of the valve handle. As indicated, valve 17 has in its central portion a large arcuate groove or recess 24, a portion of which always registers with the passage 25 leading to the rear end of the piston chamber, connecting the same either with the fluid inlet A or with an atmospheric exhaust port 26. The valve also has a small groove or recess 27 which may register with fluid inlet A alone, as in Fig. 3, or pass pressure fluid in restricted amount to a passage 28 (Fig. 4) connecting by a flexible conduit 28a to the forward end of the piston chamber to drive the piston on its return stroke, or connect passage 28 to an atmospheric exhaust 29 (Fig. 5). With the valve in the position shown in Fig. 3 (handle 18 being against stop 19) the piston is at rest and the fluid inlet A is closed off. On advancing handle 18 to a mid-position between stops 19 and 20, the rear end of the piston chamber continues to be connected to the exhaust by valve recess 24 and pressure fluid in limited amount is passed to the forward end of the piston chamber by recess 27, passage 28, and conduit 28a. As shown and by preference port 25a of passage 25 is spaced somewhat from the rearward end of the piston chamber so as to be sealed or closed momentarily by piston 7 at the end of its rearward stroke, the piston then extending into a pocket from which it rebounds by the action of the air which it traps and compresses therein. This action of the piston provides an interval of time during which the operator moves valve control handle 18 to the forward position against stop 20 (Fig. 5) so that when the piston uncovers port 25a pressure fluid at full volume enters the piston chamber insuring a blow of full power. This is an important advantage over the usual practice of stopping the piston on its rearward stroke by directing the pressure fluid released by the manual control valve directly into the rearmost portion of the piston chamber. The former practice stops the piston suddenly and reverses its movement with the result that the piston is carried on its forward stroke a considerable distance before a full opening of the throttle

is accomplished with the result that the piston does not reach its maximum velocity when it arrives at the striking point. Sealing off the inlet port and utilizing trapped air to start the piston gives the operator an interval of time to throw valve 17 and when port 25a is opened on the forward stroke of the piston the motive fluid enters at full volume and pressure.

While a preferred form of the invention has been herein shown and described it is to be understood that the invention is not limited to the specific details thereof but covers all changes, modifications, and adaptations within the scope of the appended claim. 80

I claim as my invention:

A fluid pressure hammer comprising a cylinder providing a piston chamber, a piston reciprocable therein, a back head on said cylinder having a tapered cylindrical valve chamber disposed transversely of the axis of said cylinder, a closure for one end of said valve chamber having a reduced bore, a tapered valve fitting said valve chamber and disposed therein, said valve having reduced portions at its opposite ends, a handle on one reduced end to provide for manual operation of said valve, a securing member on the other reduced end of said valve to engage said closure and limit the projection of said valve within said valve chamber, resilient means interposed between said valve and said closure yielding to urge said valve toward the small end of said valve chamber, said back head having ports and passages for the pressure fluid, and means substantially centrally of said valve for controlling said ports and passages comprising a deep arcuate groove in said valve always in communication with a port leading to the rear end of said piston chamber for connecting the latter either to the pressure fluid supply or to atmosphere and a small and shallow groove at a few degrees of rotation from said first groove for registration with the pressure fluid supply to seal the same when said valve is in neutral position and in other positions to direct pressure fluid in limited amount to the forward end of the piston chamber or to vent pressure fluid therefrom, said valve having annular grooves containing lubricant and disposed on opposite sides of said controlling means for lubricating said valve and for providing a seal against leakage of the pressure fluid. 105

Signed by me at Detroit, in the county of Wayne, and State of Michigan, this 15th day of June, 1928.

EDWARD W. STEVENS.
